HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

METHOD OF MAKING UNIONS AND THE LIKE.

1,142,302.

Specification of Letters Patent.

Patented June 8, 1915.

Application filed March 12, 1913. Serial No. 753,658.

To all whom it may concern:

Be it known that I, HJALMAR G. CARLSON, a citizen of the United States, residing at Worcester, in the county of Worcester and 5 State of Massachusetts, have invented a new and useful Method of Making Unions and the like, of which the following is a specification.

The principal objects of this invention are 10 to provide a simple, inexpensive and practicable method of making pipe unions and other articles of a similar nature, having projections at their ends for receiving nuts or other fastening devices and end surfaces 15 adapted to abut against each other; to provide a method of manufacturing such articles from disk-shaped blanks of sheet metal in a minimum number of operations; and more specifically to provide an efficient 20 method of doubling a portion of the sheet metal on itself for the purpose of providing a projecting end and a surface at the end of the article suitable for abutting against a complementary surface and forming a tight 25 joint therewith.

Reference is to be had to the accompanying drawings, in which—

Figure 1 is a central longitudinal sectional view of a cup-shaped blank showing one step 30 of the operation; Fig. 2 is a similar view showing the next step; Fig. 3 is a central vertical sectional view of a set of dies for operating on the blank shown in Fig. 2; Fig. 4 is a similar view of a set of dies showing 35 the next step of the method; Fig. 5 is a similar view of another set of dies showing the final die pressing operation; and Fig. 6 is a longitudinal central sectional view of a complete union formed by this method.

40 In the manufacture of a member of a pipe union or other similar article according to this invention, a circular disk of sheet metal is the original blank which is employed. This disk is first formed by ordinary well known die pressing operations into the cup shape blank *a* indicated in Fig. 1. In this figure the sheet metal blank *a* has been shaped in simple dies to form a cylindrical portion having an end *b*. This blank is 45 then operated upon by the ordinary well known type of punch to perforate the end *b* centrally, and in Fig. 2 it is shown as having a central perforation *c* smaller than the end so as to leave a portion of the end in posi-

tion and rounded over around the outside. 55 The next step of the preferred method consists in a die pressing operation for the purpose of reducing the diameter of the open end of the blank shown in Fig. 2 while keeping the external diameter of the perforated 60 end substantially of its original size and at the same time bending in the wall which surrounds the perforation *c* so as to bring that wall into a cylindrical form inside the external wall of the blank and of the same 65 internal diameter as the reduced wall of the open end.

For this purpose the blank is placed in a set of dies as shown in Fig. 3. The dies are 70 shown as working vertically and will be so described, although of course they can be turned if desired to work horizontally or otherwise. These dies comprise a bottom member 10 having an opening at the center in which is an ejector 11 provided with a 75 central projection 11' at the top and a flat surface 11° surrounding it. On the top of the member 10 is an intermediate die member 12 having an inwardly curved circumferential surface 12' at the top of a central 80 perforation therethrough. The top part of this perforation receives the end of the blank which fits within it. On the top of this member 12 is a die member 13 having a central perforation therethrough of a diameter 85 substantially the same as the external diameter of the blank *a* and coinciding with the end of the central opening through the intermediate member 12. Beyond this member 13 is a plunger 14 adapted to enter the 90 perforation in the member 13. This plunger is provided with a smaller central plunger 15 therein projecting beyond the end thereof and held in position by a screw 15' or the like. The plunger 15 is larger in diameter 95 than the perforation *c*.

In operation, the blank as shown in Fig. 2 is placed in the member 13 with its lower open edge resting on the edge of the surface 12' of the intermediate die member 12. It 100 is shown in this position in dotted lines in Fig. 3. The plungers 14 and 15 are then brought down upon it and the first effect is the engagement of the end of the plunger 15 with the end *b* of the blank. This plunger 105 is slightly larger than the perforation *c* and consequently it tends to force the metal down in the dies 12 and 13 and at the same

time to force the inner edge of the metal surrounding the perforation c downwardly and inwardly. The effect of this is to form an inward flange b' on the top of the blank as it descends along the surface 12. It also causes the plunger 15 eventually to enlarge the opening c and descend through it. When this happens the plunger 15 moves down into the body of the blank and then 10 the plunger 14 can come into engagement with the top of the blank, as indicated in Fig. 3. At this time, the plunger 14 has the function of positively forcing the blank down into the die so as to partake of the 15 shape of the top of the surface 12' just below the top of the blank. The plunger 15 continues to perform the function of holding the inner edge of the turned over edge b' of the blank to proper internal diameter and it 20 also descends into a position in which it registers with the surface 12' and thus holds the interior of the blank at this point and prevents it from becoming smaller than the plunger 15. As the plungers descend from 25 this point, all the metal that passes below the surface 12 will assume a cylindrical form and will have an internal diameter equal to the internal diameter of the edge b' which has been forced inwardly at the top of the 30 blank. At this time the outer wall of the blank has three portions, first a' of the same size as the original blank a ; second a'' , of cylindrical form but reduced diameter, and a third portion intermediate of the two and 35 curving gradually from one diameter to the other.

The ejector 11 can be forced inwardly at the proper time to hold the end of the blank, prevent its being reduced in diameter and 40 keep that end substantially in a plane as it comes against the surface 11', then it is used as an ejector in the usual way. This operation having been completed, the next 45 operation is commenced. In this the same members 10, 13, 14 and 15 can be used if desired, or duplicates thereof, but a new die 16 and ejector 17 are shown. In this case the ejector 17 is similar to the ejector 11 except that it has a flat top surface. The die 16 is 50 a plane die fitting the die 13, or a correspondingly shaped die, and has a cylindrical passage therethrough fitting the head of the ejector 17 and of the same diameter as the external diameter of the blank at a'' . The 55 blank being inserted in this set of dies in the position shown in dotted lines in Fig. 4, the plungers 14 and 15 are brought down upon it. The effect of this operation is to bring the upper parts of the blank into a 60 more compact form and all the parts below into a true cylindrical shape with a square end. This is brought about simply by forcing the parts down into the position shown in full lines in Fig. 4.

65 The next operation is shown in Fig. 5.

Here a die like the plate 10 is provided with an ejector 18 having a head thereon inside and provided with a recess 18'. Above this is a die 19 having a central passage 19' of a diameter the same as the passage in the die 16 and having an enlargement 19 $\circ$ above it of the same diameter as the passage through the die 13. A plunger 20 is brought down upon these parts, said plunger having a main portion of a diameter equal to the diameter of the enlargement 19 $\circ$ and a reduced portion or plunger 20' of the same diameter as the plunger 15. Between these two parts of the plunger is a convex surface 20 $\circ$ for forming the final shape of the seating surface shown in Fig. 5. When the plunger is brought down it simply compresses the top part of the blank doubling the metal edge b' over on the metal below to form a top layer b'' of metal and fill up the circular recess therein by compressing the metal into it, leaving only a seam at that point. In the form shown in the drawings, the surface 20 $\circ$ is continuous so as to form a concave surface on the blank suitable for receiving the convex surface of a companion member. This pressing operation also presses out the lower surface of the enlarged part of the blank to form a substantially square shoulder at e and the cylindrical portion of the product is brought to length and thickness and receives its final pressure for shaping it. This blank A can then be screw-threaded, or otherwise fitted up as desired, its ends squared off if necessary, and it is ready for use as a female member of a pipe union or for any other purpose for which its particular shape may be designed. In Fig. 6 I have shown this member A in its complete state set up as a part of a union, said union comprising also 105 a male member F and a nut G.

It is to be observed that the member F is provided with a slight enlargement and square shoulder f for the flange of the nut G and is provided with a convex end surface suitable for fitting against the concave end surface of the other member. Also it will be seen that the female member A is provided with a solid head or enlargement for the reception of the screw thread a'' of substantially twice the thickness of the original sheet of metal from which the blank is made and having an adequate length for the screw thread and this is accomplished by comparatively simple die pressing operations without undue complications.

The dies by which these operations are performed are simple and complete in themselves and they are easily manufactured and operated.

Although I have illustrated the invention as applied to the manufacture of a part of a pipe union, I am aware of the fact that the principles thereof can be carried out in substantially the same way in the manufac- 130

- ture of other articles of a somewhat similar form and that the exact sequence of operations can be changed to some extent without departing from the scope of the invention 5 as expressed in the claims. Therefore, I do not wish to be limited to the manufacture of this specific article or to the exact order of steps or shape of dies herein shown and described, but
- 10 1. What I do claim is:—
- 15 1. A method of making an article of sheet metal which consists in forming a cylindrical cup shaped blank from a circular disk of sheet metal, perforating the end thereof, forcing a plunger larger than the perforation against the perforated end and through it into the interior of the blank, and doubling over the end of the blank in which the perforation is located.
- 20 2. A method of forming a metallic article which comprises bending outwardly and doubling over inwardly the edge of a cylindrical blank, and concaving the inner part of said doubled edge to cause the inner surfaces thereof to come into contact throughout and to fill the entire space between them, whereby the end of said blank will have substantially twice the thickness of the metal of the original blank.
- 25 3. A method of forming an article of sheet metal which consists in providing a cup shaped blank having an open end and a perforation in the other end, forcing a plunger into said blank through the perforated end to bend the edge of the perforation inwardly, forcing the walls of the open end into contact with said plunger to shape the interior thereof, and exerting pressure on the edge of the perforated end of the blank to double said edge inwardly against the plunger.
- 30 4. A method of forming an article from sheet metal which consists in providing a cup shaped blank having an open end and a perforation in the other end, and forcing a plunger into said blank through the perforated end to double the edge thereof inwardly against the plunger and to force said blank longitudinally in a set of dies to condense the doubled edge of the blank.
- 35 5. A method of forming a metallic article which consists in providing a cup shaped blank of sheet metal having an open end and a perforation in the other end, forcing a plunger into said blank through the perforated end, forcing the walls of the open end into contact with said plunger to shape the interior thereof, and exerting pressure on the edge of the perforated end of the blank to double said edge inwardly against the plunger, and to force said blank longitudinally in a set of dies to condense the doubled edge of the blank closely around said plunger, and finally compressing said doubled edge over on itself to fill the entire
- space between the two inner surfaces thereof and form a circumferential projection on the blank of substantially twice the thickness of the metal of the original blank.
6. A method of forming a metallic article 70 which consists in providing a cup shaped blank of sheet metal having an open end and a perforation in the other end, forcing a plunger into said blank through the perforated end, exerting pressure on the edge 75 of the perforated end of the blank to double said edge inwardly against the plunger and to condense the doubled edge of the blank closely around said plunger, compressing said doubled edge over on itself to fill the 80 entire space between the two inner surfaces thereof and form a circumferential projection on the blank, and at the same time pressing the end surface of said doubled portion inwardly to form a concave seating 85 surface.
7. A method of making a metallic article which consists in providing a cup shaped sheet metal blank having an open end and a perforation in its other end, placing 90 it in a set of dies, forcing a plunger against and through the perforated end of the blank into the interior thereof and simultaneously forcing a second plunger or die against the wall of the blank surrounding the perforation so as to force the blank longitudinally in the dies along with the plunger, reducing the diameter of the open end of the blank at a point opposite the end of the plunger, and continuing the motion 95 of the central plunger and surrounding plunger or die inwardly to turn over inwardly the edge of the metal surrounding the perforation.
8. A method of making a metallic article 100 which consists in providing a cup shaped sheet metal blank having an open end and a perforation in its other end, placing it in a set of dies, forcing a plunger against and through the perforated end of the blank into the interior thereof and simultaneously forcing a second plunger or die against the wall of the blank surrounding the perforation so as to force the blank longitudinally in the dies along with the plunger, reducing the 105 diameter of the open end of the blank at a point opposite the end of the plunger, whereby the end of the blank will assume a tubular form of an internal diameter equal to the diameter of the plunger, continuing the motion of the central plunger and surrounding plunger or die inwardly to turn over inwardly the edge of the metal surrounding the perforation, and finally condensing the turned-over portion and forming a valve seating surface thereon.
9. A method of making an article from sheet metal which consists in providing a cup shaped blank having an open end and a perforation in its other end, placing it in 110
- 115
- 120
- 125

- a set of dies, forcing a plunger, larger than the perforation, through the perforated end of the blank into the interior thereof and forcing the blank longitudinally in the dies 5 along with the plunger, reducing the diameter of the open end of the blank at a point opposite the end of the plunger, transferring the blank to another set of dies, forcing a second plunger through the blank and 10 simultaneously compressing the doubled portion of the metal into a small space longitudinally but keeping it of the same external and internal diameter, and finally condensing the turned-over portion and 15 forming a valve seating surface thereon.
10. A method of making an article from sheet metal which consists in providing a cup shaped blank having an open end and a perforation in its other end, placing it in 20 a set of dies, forcing a plunger larger than the perforation through the perforated end of the blank into the interior thereof and forcing a second plunger or die against the wall of the blank surrounding the perforation so as to force the blank longitudinally 25 in the dies along with the plunger, doubling

over inwardly the edge of the metal surrounding the perforation, transferring the blank to another set of dies and compressing the doubled portion at the center and inwardly until the space between the surfaces of the doubled portion is filled by the metal of the article, and finally forming a seating surface thereon.

11. A method of forming a metallic 35 article which consists in forming a cup-shaped blank having a flat end, perforating the said flat end of the cup to provide a circular opening of less diameter than the cup, doubling the inner edge of said opening 40 inwardly within the cup so that its entire outermost surface relative to the center of the blank is brought directly into contact with the inner surfaces of the side walls of the cup and threading the blank. 45

In testimony whereof I have hereunto set my hand, in the presence of two subscribing witnesses.
